Attorney.

UNITED STATES PATENT OFFICE.

JOHN B. HAUG, OF ST. BENEDICT, KANSAS.

CAR-BRAKE.

SPECIFICATION forming part of Letters Patent No. 782,961, dated February 21, 1905.

Application filed January 11, 1904. Serial No. 188,532.

To all whom it may concern:

Be it known that I, JOHN B. HAUG, residing at St. Benedict, in the county of Nemaha and State of Kansas, have invented certain useful 5 Improvements in Car-Brakes; and I do hereby declare that the following is a full, clear, and exact description of the invention, such as will enable others skilled in the art to which it appertains to make and use the same, reference 10 being had to the accompanying drawings, which form a part of this specification.

This invention relates to a new and novel improvement in car-brakes.

The object of my invention is to provide a 15 car-brake so constructed that the car-wheel will be engaged upon opposite points, the friction being applied to the faces of the wheel instead of to the peripheral surface of the wheel; and my invention embodies certain 20 other combinations, as will be described more fully hereinafter and finally pointed out in the claims.

In the accompanying drawings I have shown 25 in Figure 1 a bottom view of a car-brake embodying my invention. Fig. 2 shows a top view of a car-brake constructed according to my invention with portions removed, while Fig. 3 shows an end view of my car-brake.

In carrying out the aim of my invention I 30 use a suitable supporting-bar A, of any suitable material, which at each end is provided with the extensions 4, as clearly disclosed in Fig. 1. This supporting-bar A is provided at opposite points and near each end with the 35 projecting ears 2 2' and 3 3', as clearly disclosed in Fig. 1. Each of these ears is provided with a supporting-pin 1, and each pin supports an ordinary roller b, as disclosed in Fig. 2. Intermediate of its ends this sup- 40 porting-bar A is provided with a stub-shaft 8, which is supported above by means of a plate 7 as shown in Fig. 2, and beyond which plate 7 this stub-shaft 8 extends, as disclosed in Fig. 3. Above, this plate is provided with 45 a T-shaped operating-lever 9, to the projecting lever 9' of which is secured a suitable connecting-rod, fixed to any brake or other operating means.

Secured to the end stub-shafts f f' and to 50 the intermediate stub-shafts f' are the pin-

ions c, as disclosed in Fig. 2. These stub-shafts f f' extend through the supporting-bar A, as disclosed in Fig. 1, and above also extend through a suitable cap-plate 12, as is disclosed in Fig. 2, these cap-plates 12 being 55 secured by means of suitable bolts a, and these cap-plates 12 are also adapted to receive the pins 1, as is shown in Fig. 2, to assist in properly supporting the rollers b. Secured to one end of each of the stub-shafts f and f' is an 60 arm e, so that these stub-shafts f are in the form of rock-shafts, being actuated from side to side by means of the arms e, as is disclosed in Figs. 1 and 2. In referring to Fig. 2 it will be noticed that I use these pinions c in pairs 65 and that the arms e are extended parallel to one another and that each set of arms is united by a connecting-rod 13, secured to the arms by means of suitable pins 1.

Extending from the pin 1 of each of the 70 innermost arms e upon one side is the connecting-bar D, secured, by means of a pin 1, to the T-shaped operating-lever, while the opposite set of arms e, by means of a connecting-bar D', held by the pins 1, is also fastened to 75 the T-shaped operating-lever 9.

Held adjacent each set of pinions c upon opposite sides are the racks B and B', as is shown in Fig. 2. These racks are of such a width that the rollers b properly hold these 80 racks in engagement with the adjacent pinions c. The racks B are somewhat shorter than the racks B' and end adjacent the inner face of the car-wheels K, these racks being provided with a brake-shoe 5, as is shown in 85 the drawings, while the racks B' have an angular extension 7', to the end of which is secured a brake-shoe 5', these two brake-shoes 5 and 5' coming in alinement, there being two sets of these brake-shoes upon opposite sides, 90 so that two car-wheels are simultaneously engaged when the brake is brought into operation. In order that the brake-shoes 5 and 5' may normally be held apart, permitting the free rotation of the car-wheels K, I provide the 95 spring 14, secured by means of the pins 1, this spring at one end being fastened to the bar A and at the opposite end, to the T-shaped operating-lever 9, so that normally these brake-shoes are held apart. Now when it is desired 100

to apply the brake the operator would draw the connecting-rod 10 forward by any suitable means, which would rock the connected stub-shafts f and f' , actuating the pinions c to carry 5 the racks B and B' toward one another, so that the brake-shoes 5 and 5' would travel toward one another and between them impinge on the car-wheel K, as is disclosed in Figs. 1 and 2, to check the rotation of the car-wheel. As 10 soon as the connecting-rod is released the spring 14 actuates the mechanism to release the brake-shoes.

The supporting-bar A may be secured to the bottom of the car by any suitable means, 15 such as by means of a chain or rod, or, if desired, these supporting-bars A may be secured in any suitable manner to the car-axles. Further, it is of course understood that where 20 cars are provided with four or more wheels each set of wheels could be provided with one of my brakes.

In Fig. 3 I have disclosed a side view illustrating the position of the outer brake-shoes 5'.

This brake is adapted to be used in connection 25 with street-cars, railway-cars, automobiles, and, in fact, any ordinary vehicle, as the bar 10 could be operated by foot. The brake engaging the side or tire of the wheel would not damage any elastic tire that might be secured 30 to the wheel should this brake be used in connection with an automobile or pleasure vehicle.

It is of course understood that the mechanism 35 may be made of suitable sizes to accommodate the sizes of the various vehicles in connection with which the same would be used.

Having thus described my said invention, what I claim as new, and desire to secure by United States Letters Patent, is—

40 1. In a brake, the combination of the following mechanism, to wit: a supporting-bar, an operating-lever pivotally secured to said sup-

porting-bar, a pinion secured to said supporting-bar near each end, a connecting-rod securing each pinion to aforesaid operating-lever, a 45 rack in engagement with each pinion upon one side, said rack ending adjacent one face of a suitable car-wheel, and a second rack in engagement with a pinion, said second rack being provided with an extension bringing 50 the same in engagement with a suitable car-wheel at a point opposite said first-mentioned rack.

2. In a device of the character described, the combination with a supporting-bar, of an operating-lever, a spring to normally force said operating-lever in one direction, a rock-shaft journaled in each end of said supporting-bar, a bar extending from each rock-shaft and secured to said operating-lever, a pinion mounted 60 upon each rock-shaft, a rack in engagement with each of said pinions, a brake-shoe secured to the end of said rack, said brake-shoe being adapted to come into engagement with the inner face of a suitable car-wheel, a supporting- 65 roller positioned adjacent said rack holding said rack in engagement with its pinion, a second rack in engagement with each pinion, a second roller holding said second rack in engagement with its pinion upon the side opposite 70 the first-mentioned rack, and a brake-shoe secured to each of said second-mentioned racks adapted to engage the face of a suitable car-wheel at a point opposite where the same is engaged by aforesaid first-mentioned brake- 75 shoe, all arranged substantially as and for the purpose set forth.

In testimony whereof I have affixed my signature in presence of two witnesses.

JOHN B. HAUG.
